JOHN WOLF, OF TOPEKA, KANSAS.

LOCK.

1,310,774.

Specification of Letters Patent. Patented July 22, 1919.

Application filed May 7, 1919. Serial No. 295,363.

To all whom it may concern:

Be it known that I, JOHN WOLF, a citizen of the United States, residing at Topeka, in the county of Shawnee and State of Kansas, have invented certain new and useful Improvements in Locks, of which the following is a full, clear, and exact description, reference being had to the accompanying drawings, forming a part hereof.

10 The present invention is directed to improvements in locks, and particularly those employed in connection with wardrobe trunks for locking one of the hinged sections of the trunk to the main or body portion, the object sought being to provide a lock with a latch-bolt that can be manipulated only from the inside of the trunk to which access is first had by the lifting or opening of a lid which is itself locked to the 15 trunk by a key-lock of any available type. A further object is to provide a lock which may be either hand-operated, or which may be automatically actuated by the closing movement of the lid; one which is simple in 20 construction, reliable, and one possessing further and other advantages better apparent from the following detailed description in connection with the accompanying drawings in which—

30 Figure 1 represents a front elevation of a wardrobe trunk showing one form of my invention applied thereto; Fig. 2 is an inside plan of the lock mechanism detached from the trunk; Fig. 3 is an enlarged longitudinal section through the lock on the line 3—3 of Fig. 1; Fig. 4 is a side elevation of the lock with parts broken away with the walls of the trunk in section; Fig. 5 is a cross-sectional detail on the line 5—5 of Fig. 4; 35 Fig. 6 is a similar view with the keeper mechanism removed; Fig. 7 is a cross-sectional detail on the line 7—7 of Fig. 6; Fig. 8 is a detached plan view of the keeper; Fig. 9 is a detached side view of the keeper mechanism; Fig. 9^a is a detached inner face view of the guide strip for the keeper; Fig. 9^b is a perspective of the latch-bolt detached; Fig. 9^c is an end view of the locking leaf showing the outer cover or cap-piece and the inner casing forming the housing for the

latch-bolt; Fig. 10 is a vertical sectional view of the trunk showing an inside view of the actuating mechanism of a modified form of lock; Fig. 11 is an enlarged inside plan of the modified lock controlled by the mechanism shown in Fig. 10; Fig. 12 is a plan of the keeper mechanism of the modified lock; and Fig. 13 is a side view of the mechanism shown in Fig. 12.

Referring to the drawings, and for the present to Figs. 1 to 9^c inclusive, T, represents the main or relatively stationary section of a wardrobe trunk, T' the vertical horizontally swinging section hinged thereto, and L, the top lid or cover as well understood in the art. The lock to which the present invention is directed is herein shown applied to the swinging section T', said lock serving to lock the section T' to the section T. This application of the lock of course is only by way of example, as the invention may be applied to any purpose known to the art. The improved lock comprises a plate 1 (secured to the section T of the trunk) to which is hinged a leaf 2 to the inner face of which there is secured at the center thereof and adjacent to the hinge axis of the leaf one end of a flexed spring 3, the free end whereof when the section T' is closed and the trunk is locked, bears against the outer face of the adjacent end of a plate 4 secured to the swinging section T' of the trunk, said plate 4 being formed with a hollow substantially U-shaped rib formation 5 terminating in enlarged pockets or recesses 6, said rib being contoured to snugly encompass the leaf 2 and protect the same when the parts are locked, the pockets 6 being intended to receive and guide the tongues 7 formed on the plate 1. Disposed symmetrically on opposite sides of a medial longitudinal line of the plate 4 and directly across the hollow rib 5 are lugs 8, 8, the plate being provided with a central opening O from which leads a recess O' at a point midway between, and adjacent to, the lugs 8, 8, said recess being designed to receive the locking end of the latch-bolt as presently to be more fully described. The opening O is bounded by a circular rim 9, the latter being formed with an

offset 9' conforming in contour to, and bounding the recess O' aforesaid. The leaf 2 is formed with an inwardly projecting marginal flange *a* which, when the leaf is closed, snugly engages the inner walls of the rib formation 5, 6 (Fig. 3) the free edges of the flange resting against the outer surface of the plate 4. The leaf carries on its under side a circular housing or casing 10 the wall of which is provided with a cut-away portion or recess *r* at a point opposite the offset 9' of the rim 9, a suitable cup-shaped cover or hood 11 being passed over the walls of the casing to protect the latch mechanism mounted in the casing and to be presently described. The cover 11 is provided with a cut away portion or opening *h* alining with the recess *r* of the housing (Fig. 9c) to permit of the free passage there-through of the sliding latch-bolt to be presently described. The cup or cover 11 is secured to the walls of the casing 10 by a pin 12 extending diametrically across the chamber of the casing at right angles to the path of reciprocation of the latch-bolt.

In the present embodiment of my invention the latch-bolt 13 (operating through the recess *r* opening *h*, and in the offset 9') terminates at its inner end in two arms 14, 14, forming in effect a yoke between whose arms is mounted an expansion spring 15 one end of which is received by a socket *i* at the base of the yoke (Fig. 2), the opposite end being coiled about a pin or stud 16 carried by the wall of the casing 10, the tension of the spring tending to force the latch-bolt outwardly or into the offset 9' of the rim 9. The outward movement of the latch-bolt is limited by the feet or lugs 17 terminating 40 the yoke arms 14 and projecting outwardly therefrom at substantially right angles thereto, said feet being arrested by the pin 12 when the latch-bolt has been moved the desired distance under the action of the spring 15. The feet 17 ride with their free ends along the inner face of the leaf 2, said feet being guided on the sides by the ribs or guides 18 disposed on the inner face of the leaf 2 and projecting into the chamber 50 of the casing 10 in which the latch-bolt and its operating parts are confined.

It will be seen from Fig. 3, that the tendency of the flexed spring 3 is to force or cause the leaf 2 to swing outwardly or to an 55 open position (see dotted position of the leaf in said figure) in the event said leaf is released from its locked position. The locking of the leaf is effected by the locking of the latch-bolt 13, that is to say, by preventing the swinging of the bolt outwardly through the opening O and its recess O'. The locking member for the latch-bolt comprises a sliding keeper or plate 19 the same being of a form such as shown in Fig. 8, and 60 provided with the terminal lugs 20 and 21

respectively, the lug 20 having secured thereto the operating rod or stem 22 guided by suitable straps 23 on the inner wall of the swinging trunk section T', and terminating at the free end in a finger-hold or eye 24, 70 to which access is had by the opening of the lid L of the trunk, the lid being locked by a key-lock 25 of any approved type as well understood in the art. The body of the keeper plate 19 comprises the portions 75 *d*, *e*, offset from one another (Fig. 8), the portion *d* operating as the keeper proper. It will be observed that the walls of the offset 9' of the rim 9 do not contact with the inner face of the plate 4, but are separated therefrom by a slit or passageway *s* to allow for the free sliding movement there-through of the portion *d* of the keeper-plate. When the portion *d* is opposite the latch-bolt 13, it covers the recess O' of the opening O, so that the bolt can not swing outwardly through the openings O, O', (Fig. 3). By moving the keeper sufficiently to withdraw the portion *d* thereof from opposite the locking terminal of the latch bolt, 80 the latter is left free to pass through the recess O' (and hence through the opening O) thereby permitting the leaf 2 to swing open under the action of the flexed spring 3. To effect release of the latch-bolt the keeper 95 19 must be moved sufficiently to bring the cross edge *t* of the portion *d* (Fig. 8) past the side of the recess O' toward which the keeper is being moved, the direction of movement being indicated by the arrow adjacent 100 the rod 22 in Fig. 2. The mounting for the sliding keeper plate is as follows: The lugs 8, 8, are embraced by the bent terminals or arms 26 of a plate or metal strip 27 one edge of which is provided with a tongue or 105 lip 28 bent at right angles to the strip (Fig. 9a), said tongue serving as a guide for the adjacent side of the keeper which operates between the tongue and the plate 4 (Figs. 3, 4). The tongue 28 is originally stamped 110 in the plane with the strip 27 and subsequently bent into the position described, the unfolded position of the tongue being shown dotted in Fig. 9a. The lugs 8, 8, and terminal arms 26, of the strip 27 are traversed 115 by a pin or stem 29 by which the strip is secured to said lugs, the stem passing freely through the lug 21 of the keeper 19 and serving as a guide therefor. Coiled about the stem 29 is an expansion spring 30 one 120 end of which bears against the inner face of the lug 21 of the keeper 19, the opposite end bearing against the adjacent lug 8 as a fixed abutment (Fig. 2). The spring 30 tends to force the keeper in proper direction 125 to bring the portion *d* thereof opposite the recess O' and hence prevent the latch-bolt 13 from swinging outwardly; and as long as the latch-bolt can not swing outwardly, the spring 3 can not force the leaf 2 to open 130

position to permit the parting of the section T' of the trunk from the section T, the latch-bolt being carried by said leaf 2. It will be seen (Fig. 3) that when the leaf 2 is closed, the rim 9 of the plate 4 carried by the trunk section T' receives the casing 10 and cover 11 carried by the leaf, thereby locking the section T (which carries the plate 1 to which the leaf 2 is hinged) to the section T' (which carries the plate 4) the pockets or recesses 6 of the latter receiving and guiding the tongues 7 of the plate 1 when the section T' is swung to closed position about its hinge axis, it being understood that the section T' is hinged to the section T on the side opposite to that shown in Fig. 1, the hinges not being shown because well understood in the art.

It will be seen from Fig. 2 that a draft or pull on the rod 22 will withdraw the portion *d* of the keeper out of the path of oscillation of the latch-bolt 13, permitting the latter to release the leaf 2, whereupon the leaf will be forced outwardly to open position under the action of the flexed spring 3 bearing with its free end against the plate 4, thereby permitting the section T' to be swung to open position, the two sections T, T', parting along the seam *m* covered by the band or valance 31 which in the present example is shown as being secured to the section T. To lock the trunk, the operator releases the rod 22, swings the section T' to closed position against the section T and locks the lid L by the key-lock 25. Thereupon the leaf 2 is pressed to locking position against the tension of the spring 3, the rounded surface *w* of the descending or oscillating latch bolt riding freely over the longitudinal edge *h* of the section *d* of the keeper, this action forcing back the bolt and compressing the spring 15. When finally the free edge of the bolt has passed off the edge *h* of the keeper the spring 15 automatically projects the bolt outwardly behind the keeper, thus locking the leaf 2 to the plate 4. In this respect the latch-bolt operates as any other spring-controlled bolt, an operation familiar to those skilled in the art.

In the form of invention above described the keeper 19 must be moved manually to release the latch-bolt 13; but I may release the bolt automatically by the opening of the lid L, as shown in the modification in Figs. 55 to 13 inclusive. To accomplish this, I simply reverse the action of the spring controlling the keeper. In this modification I employ a keeper 19' of substantially the same construction as the keeper 19 except that the section corresponding to the section *e* terminates at the inner end in a perforated lug or lip 21' (Figs. 9, 12), one end of the spring 30' engaging said lug, the other end bearing against the adjacent lug 8 of the

plate 4. When the keeper is in locking position the spring is at compression and must be allowed to expand to cause the keeper to move to unlocking position. This is just the reverse of the action of the spring 30 in the first form described. In the modification the rod 22 terminates at the top in a plate 32, which, when the lid L is closed is engaged by an angle-bracket or equivalent impinging member 33 secured to the inner wall of the lid, the member 33 depressing the rod 22 and driving the keeper to locking position and thereby compressing the spring 30'. On the other hand, and obviously, when the lid L is thrown open, the bracket or impinging member 33 is withdrawn from the plate 32 thereby releasing the rod 22 and allowing the spring 30' to expand. In this expansion the keeper 19' is automatically forced to unlocking position thus releasing the latch-bolt and permitting the leaf 2 to be forced outwardly to unlocking position under the action of the flexed spring 3 the same as in the first form described. With the exceptions above noted the modification is the same as the main form and corresponding parts are identified by the same reference numerals and symbols. In the modification the keeper is forced to locking position by the closing of the lid L, the raising of the lid permitting the keeper to be automatically forced to unlocking position by the spring 30'. In the first form described the keeper is forced to locking position by the spring 30 and must be pulled to unlocking position manually after the lid L is opened to permit access to the interior of the trunk. It is obvious that the lock may be changed in many details without departing from the nature or spirit of the invention. It is further obvious that the lock need not be restricted in its application to trunks. The lock here described (or its equivalent) may be said to comprise two sections, the first section comprising the plate 1 and the leaf 2 with its appurtenances, and the second section comprising the plate 4 and parts carried thereby. When these two sections are moved to locking position, that is when the tongues 7 have fully entered their recesses 6, the leaf 2 of the first section is ready to be folded against the complementary section, the casing 10 and its cover 11 freely passing through the opening O, O', of said complementary section and entering the rim 9, the latch-bolt automatically locking behind the keeper 19 in the manner previously described. As obvious from the drawings, the movement of the keeper 19 is in the plane of the plate 4 and in the plane of the recess O', the oscillation of the leaf 2 and that of its latch-bolt 13 being across the path of movement of the keeper.

Having described my invention what I claim is:

1. A lock comprising two sections movable into position for locking, a spring-controlled leaf mounted on one section and foldable against the opposite section, the latter section being provided with an opening, a latch-bolt casing carried by the leaf of the first section and receivable by the opening 10 of the opposite section for a locking position of the sections, a spring-controlled latch-bolt in the casing carried by the leaf, and foldable therewith to and from the opposite section, and a keeper on the last-mentioned section movable across the path of movement of the latch-bolt to and from the opposite lock section.

2. A lock comprising two sections movable into position for locking, a spring-controlled leaf hinged to one section and oscillating to and from the opposite section, the latter section being provided with an opening and a communicating recess leading therefrom, a casing carried by the leaf and receivable by the opening of the opposite section, a spring - controlled latch - bolt mounted in and operating through the casing wall and terminating in a locking end receivable by the recess aforesaid, a keeper 30 on the opposite section movable in the plane of the recess and operating to cover and uncover the same, the leaf and its latch-bolt oscillating across the path of movement of the keeper, the bolt being provided with a 35 formation to permit the bolt to yield upon engagement with the keeper with a closing movement of the leaf and finally be released and spring behind the keeper to secure the leaf to the opposite section of the 40 lock.

3. A lock comprising two sections movable into position for locking, a leaf hinged on one section and oscillatable to and from the opposite section, a spring secured at one 45 end to the leaf and bearing with its free end against the opposite section, the latter being provided with an opening and a recess leading therefrom, a rim and an offset therefor on the opposite section bounding said opening and recess respectively, a casing on the leaf receivable by the opening and rim aforesaid, a spring-controlled latch-bolt mounted in the casing and operating through the walls thereof and terminating 55 in a locking end receivable by the offset of the rim, a spring-controlled keeper mounted on the opposite section and movable in the plane of and across the recess of the opening in said section in front of the locking 60 end of the latch-bolt, the latter having a rounded terminal free to ride over the edge of the keeper with a closing movement of the leaf to permit the bolt to yield and subsequently be forced behind the keeper by

the action of the spring controlling the bolt, 65 and means for moving the keeper out of the path of oscillation of the bolt to permit the spring secured to the leaf to force the latter to open position.

4. In a lock of the character described, a locking leaf, a casing thereon provided with a recess in the wall thereof, a cup-shaped cover passed over the casing and having a peripheral opening alining with the recess in the casing wall, a latch-bolt having an outer 70 locking end operating through the recess and opening aforesaid, the bolt having an inner forked terminal in the casing, an expansion spring having one end engaging the bolt between the fork members, a suitable 75 abutment for the opposite end of the spring, terminal feet on the fork arms bearing against the inner surface of the leaf, guides in the casing bearing against the outer sides of the feet, a pin spanning the casing and 80 disposed across the path of the feet of the fork arms of the bolt for limiting the movement of the bolt in one direction, said pin serving to secure the cover to the casing, and 85 a keeper for the latch-bolt. 90

5. In a lock of the character described, a section comprising a plate provided with an opening and a recess leading therefrom, a rim bounding the opening and provided with an offset bounding the recess, the walls of 95 the offset being spaced from the adjacent face of the plate to form a passage-way or slit, a keeper-plate slidable through said slit across the recess, a complementary section, a leaf hinged thereto, and a spring-100 controlled latch-bolt terminating in a rounded face operating across the edge of the keeper plate to permit the bolt to pass behind the keeper and lock the leaf to the plate. 105

6. In a lock of the character described, a plate, a pair of lugs carried thereby and spaced apart, a strip spaced from the plate and terminating in arms embracing the lugs aforesaid, a guide tongue formed on the 110 edge of the strip adjacent the plate and disposed at right angles to the plane of the strip, a pin traversing the lugs and arms of the strip aforesaid, a keeper having a perforated lug passed loosely over the pin, a 115 spring coiled about the pin and having an end engaging the lug of the keeper and the opposite end the adjacent lug of the plate, and means for actuating the keeper in one direction against the tension of the spring. 120

7. In a lock of the character described, a section provided with a hinged leaf, a spring-controlled latch-bolt on said leaf, a complementary section, and a keeper on said section movable across the path of movement of the latch-bolt on the first section. 125

8. In a lock of the character described, a section provided with a hinged leaf, a

spring for forcing the leaf to an open position, a spring-controlled latch-bolt on the leaf, a complementary section, means on the respective sections for preventing separation of the sections when the leaf is swung into locking engagement with the complementary section, and a keeper on the complementary section movable across the path of movement of the latch-bolt of the first

section to hold the leaf against an opening 10 movement under the action of its operating spring.

In testimony whereof I affix my signature in presence of two witnesses.

JOHN WOLF.
